UNITED STATES PATENT OFFICE.

JÓSEF JUHÁSZ, OF UNITY STATION, PENNSYLVANIA.

RAIL-JOINT.

1,053,293.

Specification of Letters Patent. Patented Feb. 18, 1913.

Application filed June 5, 1912. Serial No. 701,820.

To all whom it may concern:

Be it known that I, JÓSEF JUHÁSZ, a subject of the King of Hungary, residing at Unity Station, in the county of Allegheny and State of Pennsylvania, have invented certain new and useful Improvements in Rail-Joints, of which the following is a specification, reference being had therein to the accompanying drawing.

10 This invention relates to a metallic tie and rail fastener, and the objects of my invention are to provide a tie of the I-beam construction that can be used for supporting rails, and to furnish the top flanges of the tie with a novel fastener for preventing vertical and lateral displacement of a rail upon the tie.

Further objects of my invention are to provide a metallic tie and rail fastener that 20 eliminates the use of splice-bars, clips, nuts and bolts, and to accomplish the above result by a mechanical construction that is strong and durable, inexpensive to manufacture and highly efficient for the purposes for which it is intended.

I attain the above objects by a mechanical construction that will be hereinafter specifically described and then claimed, and reference will now be had to the drawing, 30 wherein:

Figure 1 is a side elevation of a portion of a tie in accordance with this invention. Fig. 2 is an end view of the same. Fig. 3 is a plan. Fig. 4 is a perspective view of a rail chair, and Fig. 5 is a side elevation of a portion of the tie illustrating a modified form of rail fasteners.

The reference numeral 1 denotes a tie of the I-beam construction, said tie having 40 base flanges 2 and top flanges 3. The top flanges 3, adjacent to the ends thereof are provided with transverse dove-tail seats 4 and arranged in said seats are the depending dove-tail tongues of rail chairs 6. The 45 rail chairs 6 are provided with openings 7 to receive rivets or pins 8 employed for

connecting the chairs to the top flanges 3 of the tie.

Each rail chair has outer longitudinal fasteners 9 that engage and overhang the 50 outer base flange 10 of a rail 11 mounted on the chairs. The inner edge of the chair has a longitudinal rib 12, which intermediate the ends thereof, is provided with a lug 13 preferably formed integral with said rib. 55 The lug 13 is adapted to extend into a notch 14 provided therefor in the inner base flange 15. The lug 13 prevents longitudinal displacement of the rail relatively to the chair and the outer rail fastener 9 prevents vertical displacement of the rail. 60

In Fig. 5 in the drawing there is illustrated a modification of the invention, wherein a rail chair 16 has inner and outer splice bars 17. This form of chair is placed 65 in engagement with the flanges of a rail prior to the chair being placed in engagement with the tie.

What I claim is:—

In a metallic tie and rail fastener, the 70 combination with a tie of the I-beam construction that has the top flanges thereof provided with a dove-tail transverse seat, of a chair having a depending dove-tail tongue adapted to engage in the seat of said 75 tie, rivets connecting said chair to the top flanges of said tie, an integral outer rail fastener carried by said chair and adapted to engage and overhang the outer base flange of a rail placed upon said chair, a 80 longitudinal rib carried by the inner edge of said chair, and a lug formed integral with said rib and adapted to engage in a notch provided therefor in the inner base flange of a rail mounted upon said chair. 85

In testimony whereof I affix my signature in the presence of two witnesses.

JÓSEF JUHÁSZ.
